(57) **CLAIM**

The ornamental design for a docking cradle, as shown and described.

DESCRIPTION

This application is related to U.S. Design patent application for Battery And Docking Cradle, Ser. No. 29/726,755 by G. Sung, filed on even date herewith, and U.S. Design patent application for Battery, Ser. No. 29/726,756 by G. Sung, filed on even date herewith.

FIG. 1 is a perspective view of the top, front and left sides of a docking cradle shown in a typical use configuration; FIG. 2 is a front side elevation view of the docking cradle; FIG. 3 is a right side elevation view of the docking cradle; FIG. 4 is a rear side elevation view of the docking cradle; FIG. 5 is a left side elevation view of the docking cradle; FIG. 6 is a top plan view of the docking cradle; and, FIG. 7 is a bottom plan view of the docking cradle. The broken-lines in the drawings illustrate portions of the docking cradle that form no part of the claimed design.
